INVENTOR.
Louis Cottella
BY ATTORNEY.

UNITED STATES PATENT OFFICE

LOUIS COLELLA, OF DETROIT, MICHIGAN

RIDING DEVICE

Application filed December 26, 1928. Serial No. 328,335.

My invention relates to a new and useful improvement in a riding device adapted for use by children and has for its object the provision of a device of this class which will afford amusement to the user and require the user to exercise.

Another object of the invention is the provision of a device of this class which will be simple in structure, economical of manufacture and highly efficient in use.

Another object of the invention is the provision of a device of this class on which the rider may, through the effect of a spring, produce a bouncing while in the rider's seat 15 and at the same time propel the device through the bouncing effect.

Other objects will appear hereinafter.

The invention consists in the combination and arrangement of parts hereinafter described and claimed.

The invention will be best understood from a reference to the accompanying drawings which form a part of this specification, and in which,

25 Fig. 1 is a side elevational view of the invention with parts broken away and parts shown in section.

Fig. 2 is a top plan view of the invention.

30 Fig. 3 is a fragmentary sectional view taken on line 3—3 of Fig. 1.

Fig. 4 is a view taken on line 4—4 of Fig. 1.

Fig. 5 is a side elevational view of a modified form of the invention.

35 Fig. 6 is a side elevational view of a modified form of the invention with parts broken away and parts shown in section.

Fig. 7 is a top plan view of the form shown in Fig. 6.

40 Fig. 8 is a top plan view of a chassis used in the modified form.

Fig. 9 is a fragmentary sectional view of the form shown in Fig. 8.

In the form shown in Fig. 1 I provide a 45 base 15 to which is attached the angularly turned end 16 of the spring bar 17. Secured to the spring bar 17 are image forming blocks 18 and 19 which are spaced apart. Formed in the block 18 is a recess 50 20 in which is inserted one end of a coil

spring 21, the other end engaging the body engaging plate 22 which cooperates with the body engaging plate 23 to snugly engage the body of the rider so as to prevent falling from the device. A coil spring 24 55 engages at one end in the recess 25 formed in the block 19, these coil springs serving to press the plates 22 and 23 toward each other. A seat plate 26 is positioned on one end of a coil spring 27, the other end of 60 which engages the horizontally directed portion 28 of the leaf spring 17. A foot rest 29 projects laterally outwardly from each side of the leaf spring 17. This spring 17 is projected through slots 30 and 31 which 65 are formed in the pyramidal shaped housing 32 in which is positioned a helical spring 33.

In use, the occupant sitting on the seat plate 26 may through a bouncing of the body 70 bring about an oscillation of the spring 17. Arcuate plates 34 are secured to opposite ends of the base 15 and serve to support the same and prevent tipping of the device 75 sideways.

A device constructed in this manner will afford considerable amusement to a child while at the same time requiring the desired exercise. It is believed obvious that the blocks 18 and 19 may be of any desired 80 shape to simulate animals or other images. Projecting upwardly from the plate 28 at opposite sides are side rails 35 which telescope with the plates 36 secured to the seat plate 26 so that the seat plate is guided 85 in its movement toward and from the horizontally directed portion 28. A hand hold 37 is projected through the block 18.

In Fig. 5 I have illustrated a slightly modified form in which a leaf spring 38 90 is provided with horizontally directed portion 28 and secured to the blocks 18 and 19 constructed as described. The leaf spring 38 is secured to a V-shaped spring 39, one end of which is secured to the base 15. An 95 extension 40 of the leaf spring is provided with a contact member 41 adapted to engage the block 42 which is slidably mounted in the slot 43 formed in the upright 44, which is secured to and projects upwardly 100

from the base 15, graduations being formed on the upright 44 on opposite sides of the slot 43. A bell 45 is mounted at the upper end of the slot 43 so that when the child 5 has effected the bouncing to a predetermined degree, the slot 43 will be driven upwardly so as to strike and ring the bell 45 thus forming the device so that there is an incentive for the child to spring the member 10 38 to a predetermined degree, thus requiring an increased exercise of the rider.

In the form shown in Fig. 6, I have provided a bed or base 46 mounted on rear wheels 47 and 48 and provided with front 15 wheels 49 and 50, these wheels 49 and 50 being fixedly mounted on the shaft 51. Fixedly mounted on the shaft 51 is a gear 52 meshing with a gear 53 which is rotatably mounted on the shaft 54 and carries on its 20 face, so as to be rotatable therewith, a ratchet wheel 55 which is designed to be engaged by the dog 56 which is swingably mounted on the rockable link or lever 57. This lever 57 is pivotally connected at 25 one end to the link 58 which connects to the angularly turned end 59 of the bell 60 which is provided with the horizontally directed portion 61 on which the blocks 18 and 19 are mounted, together with the seat forming 30 parts described for Fig. 1. A spring 62 is connected at one end to the base 46 and at its opposite end to the portion 59.

In operation, when the child effects a 35 bouncing of the seat or a rocking of the bell 60 downwardly, the dog 56 will be moved forwardly around the ratchet wheel 55 and upon reverse rocking of the bell 60, the ratchet wheel will be caused to rotate, thus propelling the vehicle forwardly.

40 In Fig. 8, I have shown a modified form in which a chassis comprising side rails 63 and 64 are connected by the cross bars 65 and 66. This chassis is supported on the shaft 67 on which are mounted wheels 68 and 69. Projected through the forward end of the chassis side rails 63 and 64 is a crank shaft 70 on which is fixedly mounted the 45 wheels 71 and 72. A cross bar 73 is mounted on the base of the seat 74 which is attached to a leaf spring 75 constructed and mounted as the leaf spring 17. Downwardly turned ends 76 of the bar 73 are adapted to engage outwardly, projecting lugs 77 which are mounted on the disc 78 which is 50 fixedly mounted on the crank shaft 79. The cranks of the crank shaft 70 are connected to the cranks of the crank shaft 79 by connecting rods 80. Fly wheels 81 are mounted 55 on the crank shaft 79.

60 In operation as the bouncing of the seat is effected, the disc 78 will cause the crank shaft 79 to rotate, thus propelling the vehicle.

65 With a device constructed in the manner indicated, a durable structure is possible

and one which may be economically manufactured.

While I have illustrated and described the preferred form of my invention, I do not wish to limit myself to the precise details of structure shown but desire to avail myself of such variations and modifications as come within the scope of the appended claim.

Having thus described my invention what 75 I claim as new and desire to secure by Letters Patent is:

In a device of the class described a seat comprising spaced body members movable relatively to each other; resilient means for 80 normally pressing said members toward each other and resisting relative withdrawal of said members; a seat forming plate movably mounted; and resilient means for normally resisting movement of said plate.

85 In testimony whereof I have signed the foregoing specification.

LOUIS COLELLA.
